CLAIM

The ornamental design for an angularly adjustable pneumatic hammer, as shown and described.

DESCRIPTION

FIG. 1 is a side elevational view of the angularly adjustable pneumatic hammer showing our new design, the opposite side being a mirror image thereof;

FIG. 2 is a top plan view thereof;

FIG. 3 is a bottom plan view thereof;

FIG. 4 is a right end elevational view thereof;

FIG. 5 is a left end elevational view thereof;

FIG. 6 is a side elevational view thereof with the tool handle shown in the angled position.
